United States Patent Office

Des. 221,362
Patented Aug. 3, 1971

221,362

CHECK STAND OR SIMILAR ARTICLE

Oscar Ray Henderson, Covina, Calif.
(12774 Islandview Ave., Uniontown, Ohio 44685)

Filed Feb. 12, 1970, Ser. No. 21,416

Term of patent 14 years

Int. Cl. D6—01

U.S. Cl. D80—2

FIG. - 1

FIG. - 2

FIG. - 3

FIG. - 4

FIG. - 5

FIG. 1 is a top view of a check stand or similar article, showing my new design;

FIG. 2 is a front elevational view thereof;

FIG. 3 is an end view thereof;

FIG. 4 is a rear elevational view thereof; and

FIG. 5 is a view of the end opposite the end shown in FIG. 3.

I claim:

The ornamental design for a check stand or similar article, as shown.
